UNITED STATES PATENT OFFICE.

ISAAC SNOW, OF LAWRENCE, MASSACHUSETTS.

FILLING STOP-MOTION.

1,275,487.

Specification of Letters Patent. Patented Aug. 13, 1918.

Application filed July 27, 1917. Serial No. 183,174.

To all whom it may concern:

Be it known that I, ISAAC SNOW, a citizen of the United States, residing at Lawrence, in the county of Essex and State of Massachusetts, have invented a new and useful Filling Stop-Motion, of which the following is a specification.

This invention relates to a filling stop motion of the type in which the actuator is given an operative movement on alternate picks of the loom only.

Such stop motions are commonly provided with a detector coöperating with a grate mounted on the lay. When the shuttle is in the box adjacent to the stop motion the filling, if unbroken, extends across the grate and thus raises the fork or detector as the lay moves forward. The actuator is given its operative movement at the moment when the detector is thus raised to inoperative position and the loom is thus permitted to continue in operation. If the filling is broken or exhausted the detector is not raised and the actuator operates to stop the loom. Upon the alternate picks when the shuttle is in the box on the opposite side of the loom the actuator is inoperative.

Under normal conditions this method of operation is satisfactory, but it not infrequently happens that waste or filling becomes lodged on the filling fork grate, thus raising the fork or detector upon every beat of the lay, whether or not the filling is present. Under these conditions the ordinary type of filling stop motion will continue in operation indefinitely, even after the filling in the shuttle is entirely exhausted.

It is the general object of my present invention to provide a filling stop motion which will stop the loom whenever conditions arise which operate the filling fork or detector when the shuttle is in the remote box.

With this general object in view, my invention in the preferred form comprises a normally fixed stand upon which the filling fork or detector is pivoted, an actuator which is given an operative movement upon each alternate beat of the lay, connections from the actuator to the shipper through which the loom may be stopped, and means controlled by the detector effective to render said connections operative or inoperative as required.

An important feature of my invention

consists in so constructing said detector that an obstruction of the filling fork grate, as by the weft thread, with the shuttle in the adjacent box, will render said actuator inoperative, while an obstruction of the grate with the shuttle in the opposite box will render said actuator operative to stop the loom.

My invention further relates to arrangements and combinations of parts herein-after described and more particularly pointed out in the appended claims.

A preferred form of my invention is shown in the drawings, in which—

Figure 1 is a sectional elevation of my improved filling stop motion;

Fig. 2 is a view similar to Fig. 1, but showing the parts in a different position;

Fig. 3 is a top plan view of the stop motion;

Fig. 4 is an enlarged plan view of certain parts of the mechanism;

Fig. 5 is a transverse sectional elevation taken along the line 5—5 in Fig. 4, and

Fig. 6 is a detail sectional elevation showing further conditions of operation.

Referring to the drawings, my improved stop motion is shown mounted upon the breast beam 10 of a loom of a usual type. The shipper lever is indicated in section at 11 in Fig. 3, the lever being movable in a slot 12 formed in a bracket 13 secured to the breast beam 10. When the loom is in operation the shipper lever 11 is yieldingly held in a notch 14 and is engaged by the shipper finger 15 pivoted at 16 to the bracket 13.

The arm 17 of the shipper finger extends into a recess 18 (Figs. 1 and 2) formed in the lower face of a slide 19 movably mounted in a guide plate 20. The slide 19 is normally held in the position shown in Figs. 1 and 3 by the spring pressure of the shipper lever 11 acting through the shipper finger 15 and arm 17.

A stand 21 is pivoted at 22 to the rear end of the guide plate 20 and may be held in normal position by a lug 23 which engages the rear edge of the breast beam 10.

A detector or filling fork 24 is pivoted at 25 to the stand 21, the pivot 25 normally remaining in fixed position relative to the breast beam 10. The filling fork 24 is provided with a forwardly extending forked member 26, the purpose of which will be hereinafter described. The fork 24 coöper-

ates with a fork grate of the usual type, mounted on the lay and not shown herein.

An actuator 27 extends upward through the stand 21 and slide 19 and may be operatively connected to the slide 19 by a link or loop 28. This loop normally engages a projection 29 formed on the upper side of the rear portion of the slide 19. The actuator 27 is given a reciprocating motion on every alternate beat of the lay, and the mechanism for thus reciprocating the actuator may be of the usual type which commonly comprises a cam mounted on the cam shaft of the loom and making one revolution to each two picks of the loom.

Reference to Fig. 1 will show that the forked member 26 of the filling fork 24 normally extends beneath the link 28 when the parts are in operative position, with the shuttle in the adjacent shuttlebox. The actuator remains in the position shown in Fig. 1 while the lay beats up, the weft thread extending across the fork grate to the boxed shuttle moving the fork 24 to the dotted line position in Fig. 1. The member 26 and the link 28 are thus raised to their dotted line positions, and are retained in such positions until the actuator has commenced its forward movement. The link 28 then passes over the projection 29 and the slide 19 is unmoved. As the lay moves back, the fork returns to the normal full line position shown in Fig. 1.

If, however, the filling is broken or exhausted the fork remains in the position shown in Fig. 2, and the link 28 engages the projection 29 as the actuator moves forward, thus moving the slide 19 and releasing the shipper lever 11 from the notch 14, whereby the loom is stopped.

If the shuttle is not properly boxed and engages the fork 24, the stand 21 swings upward about its pivot 22, thus preventing damage either to the shuttle or to the stop motion.

I will now describe the operation of my improved mechanism when the fork grate becomes obstructed by waste or filling. If the fork is raised when the shuttle is in the box adjacent the stop motion, the actuator is rendered inoperative as above described; and the actuator and link move to the dotted line position shown in Fig. 6, in which position they remain until the shuttle is boxed at the opposite side of the loom. The lay then moves forward a second time and any obstruction upon the fork grate will again move the fork and raise the member 26 to the full line position shown in Fig. 6. At this point in the operation of the loom the actuator 27 is given its rearward movement to the position also shown in full lines in Fig. 6. Such movement slides the link 28 beneath the member 26 and into position to engage the projection 29 upon the next

forward movement of the actuator. The parts remain in this position until the next beat of the lay, when the actuator is moved forward and the loom is stopped through the action of the slide 19 on the shipper finger 15 and lever 11.

During this operation it will be noted that the member 26, being now above the link 28 is no longer effectual to render the actuator inoperative, whether or not the fork is raised by filling or waste upon the grate upon the next beat of the loom with the shuttle in the adjacent box.

I have thus provided simple and effective mechanism for stopping the loom in the regular manner upon the failure or exhaustion of filling, and also for stopping the loom whenever the fork grate becomes obstructed to such an extent as to interfere with the normal operation of the filling stop motion.

Having thus described my invention, it will be evident that changes and modifications can be made therein by those skilled in the art without departing from the spirit and scope of my invention as set forth in the claims, and I do not wish to be otherwise limited to the details herein disclosed, but what I claim is—

1. A filling stop motion having, in combination, a stand, a filling fork pivoted thereto, a slide movable independently of said stand and fork, connections through which such movement of said slide is effective to stop the loom, an actuator, a connection between said actuator and said slide, and means associated with said fork and normally effective to render said connection inoperative, but permitting said connection to become operative to move the slide and thereby stop the loom on breakage of filling and also when the path of the filling fork is obstructed at the time when the adjacent shuttle box is empty.

2. A filling stop motion having, in combination, a stand, a filling fork pivoted thereto, a slide movable independently of said stand and fork, connections through which such movement of said slide is effective to stop the loom, said slide having a projection thereon, an actuator, a link on said actuator effective to normally engage said projection and render said slide operative, and means associated with said fork effective to raise said link to inoperative position when the fork is moved.

3. A filling stop motion having, in combination, a stand, a filling fork pivoted thereto, a movable member, loom stopping mechanism controlled through said member, an actuator, a single connector from said actuator to said member, and a device operated by said filling fork effective to place said connector in operative and inoperative positions, whereby said actuator is rendered

operative to move said member and stop the loom upon breakage of filling and also when the fork is raised with the adjacent shuttle box empty.

- 5 4. A filling stop motion having, in combination, a stand, a filling fork pivoted thereto, a slide movable independently of said stand and fork, connections through which such movement of said slide is effective to stop the loom, an actuator, a rearwardly extending member on said actuator normally depressed to operatively engage said slide, and a forwardly extending portion connected to said filling fork normally positioned beneath said member and effective to raise said member to inoperative position when the fork is rocked, said portion

being moved to inoperative position above said member on the rocking of said fork when the adjacent shuttle box is empty. 20

5. A filling stop motion having, in combination, a filling fork, a slide, loom stopping mechanism controlled through said slide, means controlled by said fork effective to actuate said slide, and a stand comprising 25 fixed and movable parts, said fixed part forming a guideway for said slide, and said movable part supporting said filling fork normally in operative position, but permitting removal thereof under abnormal conditions independently of said slide. 30

In testimony whereof I have hereunto affixed my signature.

ISAAC SNOW.
